POWDER COMPACT

Mortimer L. Vogelman, Elgin, Ill., assignor to Elgin American, Inc., a corporation of Illinois

Application October 9, 1951, Serial No. 250,403

8 Claims. (Cl. 132—83)

This invention relates to a novel cosmetics case which incorporates a number of features and facilities not ordinarily found in a compact. In particular it relates to a cosmetics case including a lipstick compartment and a pill compartment harmoniously arranged, as in a representation of a bird.

One feature of this invention is that it provides a lipstick compartment substantially co-extensive with one of the body sections making up the case; another feature of this invention is that it provides a compact having a pill case; another feature of the invention is that it provides a two-piece cosmetics case cover, both halves of which swing open upon the release of a single catch member; another feature of the invention is that it provides a cosmetics case in which a double mirror is incorporated; a further feature of the invention is that it provides a platform having a turned-down portion to provide one wall of a pill receptacle.

Still other features and advantages of this invention will be apparent from the following specification and the drawings, in which:

Fig. 1 is a perspective view of an embodiment of this invention represented as a bird;

Fig. 2 shows the device of Fig. 1 with the double winged covers open to reveal a mirror;

Fig. 3 is a perspective view similar to Fig. 2 except that the mirror has been opened;

Fig. 4 is a perspective view similar to Fig. 3 except that the partition to the face powder compartment has been opened;

Fig. 5 is a bottom plan view of the cosmetics case showing the manner in which one of the single covers folds over the other;

Fig. 6 is an end view of the device showing the right wing folded over the left wing;

Fig. 7 is a perspective view of the double mirror utilized in the case;

Fig. 8 is a perspective view of the platform in which the mirror of Fig. 7 is hinged;

Fig. 9 is a front view, partially in section, taken along the lines 9—9 of Fig. 10 showing the manner in which the platform is retained in the device and also showing the lipstick tube and the design whereby the hinges fastening the wings to the main compact section are invisible when the compact is closed;

Fig. 10 is a view of the compact, partly in section, showing the wings and the mirror upraised and the pill box closed;

Fig. 11 is an enlarged broken sectional view illustrating the mode of operation of the invisible hinges employed in the device;

Fig. 12 is a sectional view taken along the lines 12—12 of Fig. 5 showing the cross-sectional contour of the two wing sections;

Fig. 13 is a sectional view taken along the lines 13—13 of Fig. 5 showing the method of operation of the catch members of both the wings and the pill compartment;

2

Fig. 14 is a sectional view showing the catch member for the mirror and powder compartment partition;

Fig. 15 is a sectional view showing the movement of the catch member of Fig. 14 just after the mirror has begun to rise; and

Fig. 16 is a sectional view of the catch member of Fig. 14 taken along the lines 16—16 of Fig. 14.

For formal wear many women prefer to dispense with a handbag and carry a small cosmetics case which, if desired, may be entrusted to the custody of an escort. The novel cosmetics case illustrated in Fig. 1 provides a single package containing all of the cosmetics likely to be required in the course of an evening.

Referring to Fig. 1 a main body section 20 cooperates with a pair of hinged wing sections 21 and 22 to define a compartment for the storage of cosmetics. Opening of the wings 21 and 22, which are spring-biased outwardly by suitable spring means (not shown), is controlled by a thumb catch 23. A head section 24, which may be withdrawn, serves as a handle for holding a lipstick container. The wing sections fold against a lid 25 which serves as the cover for a pill compartment.

Referring to Fig. 2, the thumb catch 23 has been depressed to release the wing sections 21 and 22 which have swung open on invisible hinges 26 to reveal a platform 27 in which a mirror 28 is fastened by a pair of hinges 29. A catch 30 holds the mirror 28 in place.

Referring to Fig. 3, the catch 30 has been released and the mirror 28 has assumed a vertical position with respect to the rest of the device. In Fig. 4 the catch 30 has been released still further to open a partition 31 which is positioned on the platform 27 by means of a hinge 32.

Referring to Figs. 9 and 10 the means whereby the platform 27 is positioned within the main body section is revealed. A U-shaped guide member 34 is fastened to the underside of the platform 27 and a tube 35 is passed through the guide member 34 and is anchored by means of a bolt 36 to an internal support member 37 positioned on the interior of the main body section 20 of the compact.

Referring to Figs. 9 and 11, the invisible hinges which hold the wing sections 21 and 22 to the main body section 20 may be seen to consist of a scroll plate 26a which is fastened to each of the wings 21 and 22. The scroll plate 26a forms one of the portions of the hinge 26. In co-operation with a plate 26b attached to the main body section 20 and a pin 26c it enables the wing sections 21 and 22 to be opened outward without having a hinge that is visible from the outside when the wing sections 21 and 22 are closed.

Referring particularly to Fig. 13 the pill compartment lid has a slide panel 40 on its underside which includes a pair of catch members 41 and 42. The catch member 41 engages a hook 44 on the underside of the wing 21. Thus, when the wing 22 is down and the wing 21 placed over it, the hook 44 is engaged by the catch 41 to maintain the two wing sections in closed position until such time as the thumb catch 23 is pressed. A pair of apertures 43 in the main section 20 serve to retain the lid 25 of the pill compartment in position after it has been closed.

Referring to Figs. 14, 15 and 16 the catch 30 may be seen to be a U-shaped spring member having a tip portion bent over so as to form a catch for the double mirror 28. The mirror 28 is spring-biased by a spring 28a which forces it into a position at an angle of approximately 90° with the main body section when the catch 30 is tripped. A lip 46 is engaged by the catch 30 when the mirror is in closed position.

The powder compartment 31 has a natural springiness which enables it to open slightly when a slide catch 47 (Figs. 3 and 4) is moved a sufficient distance to unblock the partition.

The cosmetics case illustrated not only provides all of the accessories normally required but also constitutes a striking accessory for formal wearing apparel. It is obvious that many modifications may be made without departing from the scope of the invention. Accordingly, it is the intention that this invention be limited only within the bounds set forth in the appended claims.

For further details of the compact disclosed in this application reference may be had to the following pending applications: Irelan Serial Nos. 250,427, 10 250,428, now Patent No. 2,688,814, and 250,429, now Patent No. 2,719,648, and Fritz Serial No. 250,415, now Patent No. 2,720,884, all filed October 9, 1951.

I claim:

1. A cosmetics compact of the character described comprising: a body section having an aperture therein disposed for the reception of a lipstick container; a pair of covers hinged to said body section, one of said covers having a portion overlapping the other; biasing means for swinging said covers outwardly; and a single latch retaining both covers in closed position. 15

2. A powder compact of the character described comprising: a body section having an aperture therein disposed for the reception of a lipstick case and a small cavity for carrying pills; a platform positioned in said body section; a lid adapted to cover said small cavity hinged to said platform; a double-faced mirror hinged on said platform; a spring for biasing said mirror whereby it assumes an angle of about 90° with respect to said platform; a pair of covers hinged to said body section, one of said covers having a portion overlapping the other; and a single latch retaining both covers in closed position. 25

3. A cosmetics case of the character described comprising: a main body section; a platform in said main body section; a mirror hinged on said platform, said mirror being spring-biased toward an open position; a pair of covers for said main body section, each of said covers occupying approximately half of the area of said platform and one of said covers overlapping the other; a hinge fastening each of said covers to said body section; said hinges being of the scroll-plate type and mounted on the inside of said body section whereby said hinges are invisible when said covers are closed; and a latch for maintaining the overlapping cover in closed position. 35

4. A cosmetics container of the character described, comprising: a main body section; a platform mounted within said main body section; a powder storage compartment within said platform; a pill compartment within said body section; a cover for said pill compartment, said cover being hinged to said platform; a pair of covers hinged to said main body section, one of said covers overlapping the other at one end thereof; a slide panel mounted on said pill compartment cover; a pair of catch members mounted on said slide panel, one of said catch members serving as a catch for said overlapping cover; and a thumb catch mounted on said slide panel whereby said slide panel may be moved a short distance to release the catch controlling said overlapping cover and an addi- 50

tional distance to release the catch for said pill compartment cover.

5. A cosmetics container of the character described, comprising: a main body section; a platform positioned in said main body section; a double-sided mirror hinged to said platform; a spring for biasing said mirror to approximately a 90° open position with respect to said platform; a latch for maintaining said mirror in closed position with respect to said platform; a pair of covers for said main body section, one of said covers having a portion overlapping the other; and means for holding said overlapping cover in closed position.

6. A cosmetics container of the character described, comprising: a main body section, said main body section defining a cavity for the storage of cosmetics; a tube adapted to receive a lipstick container in said main body section, a pair of covers hinged to said main body section, one of said covers having a portion overlapping a portion of the other cover; means for latching said overlapping cover, said means retaining both covers in closed position; and a lipstick container, said lipstick container, body section, and covers simulating the figure of a bird wherein the main body section corresponds to the body of the bird, the overlapping covers the wings of said bird, and the holding portion of the said lipstick container the head of said bird.

7. A cosmetics compact of the character described, comprising: a body section having a cavity therein disposed for the reception of a lipstick container; a platform positioned in said body section adjacent said cavity; a pair of hinged covers for said body section, one of said covers having a portion overlapping the other; biasing means for swinging said covers outwardly; and a single latch operably associated with said overlapping cover, whereby said single latch retains both covers in closed position. 30

8. A cosmetics compact of the character described, comprising: a body section styled in the form of a conventional figure, said body section having a cylindrical cavity therein disposed for the reception of a lipstick container; a platform positioned in said body section adjacent said cavity; a pair of hinged covers for said body section, one of said covers having a portion overlapping the other; biasing means for swinging said covers outwardly; and only a single latch for securing said overlapping cover in closed position, whereby said single latch retains both covers in closed position. 40
